Specification for Design.

Patented May 4, 1915.

Application filed March 8, 1915. Serial No. 12,975. Term of patent 7 years.

To all whom it may concern:

Be it known that I, JOHN T. WIGLEY, a citizen of the United States, residing at Syracuse, Onondaga county, State of New York, have invented a new, original, and ornamental Design for an Article of Manufacture, of which the following is a specification, reference being had to the accompanying drawing, forming part thereof.

Referring to the drawing, the part marked A indicates an article of manufacture to which my design is applied and the part marked B represents the design itself.

While I have shown the various parts of

the design produced in black it is to be understood that I may reproduce the design in various colors or use different colors in different parts of the design.

I claim:

The ornamental design for an article of manufacture as shown and described.

In testimony whereof I affix my signature in presence of two witnesses.

JOHN T. WIGLEY.

Witnesses:

ISABELLE HARRINGTON,
JACOB G. SMITH.
